Matter enclosed in heavy brackets [ ] appears in the original design patent but forms no part of this reissue specification; matter printed in italics indicates the additions made by reissue.

FIG. 2

FIG. 1

FIG. 1 is a front elevation of a *roof* for lighting fixture showing my new design with the standard broken away in part to indicate indeterminate length.

FIG. 2 is a top plan view thereof.

[The dominant features of my design reside in the full line portions of the drawings.]

The undisclosed rear is the same in appearance as the front shown in FIG. 1.

The body and post of the lighting fixture are shown in broken lines for illustrative purposes only.

I claim:

The ornamental design for a *roof* for lighting fixture, substantially as shown and described.
